UNITED STATES PATENT OFFICE.

PAUL SPILGER, OF FRANKFORT-ON-THE-MAIN, GERMANY.

MOTOR BELT-TENSIONING APPLIANCE.

Application filed August 29, 1921. Serial No. 496,609.

(GRANTED UNDER THE PROVISIONS OF THE ACT OF MARCH 3, 1921, 41 STAT. L., 1313.)

To all whom it may concern:

Be it known that I, PAUL SPILGER, a citizen of the German Republic, residing at Frankfort-on-the-Main, Germany, have invented certain new and useful Improvements Relating to Motor Belt-Tensioning Appliances (and for which I have obtained patents in Germany, No. 331,813, filed Mar. 11, 1919; in Great Britain, No. 147,228, filed July 7, 1920; in Holland, No. 7,931, filed Aug. 14, 1920; in France, No. 527,147, filed July 8, 1920; in Norway, No. 35,821, filed July 10, 1920; in Switzerland, No. 91,648, filed July 9, 1920; in Denmark, No. 28,806, filed July 30, 1920), of which the following is a specification.

This invention relates to improved means for maintaining a desired or proper tension in a motor driving belt when this is arranged vertically or nearly so, and is in use, and also for releasing the belt from tension when not in operation. The object of the invention is to minimize the stretching of a belt by a proper adjustment of the tension therein.

The invention consists in an improved support for carrying the motor, the support comprising a base plate or frame supported on springs, the tension of which is varied according to the stretch of the belt, and a loading device which renders it possible to maintain on the belt the tension most suitable for the load it has to transmit. The motor base plate is connected to a sub-base or floor by means of pairs of double links which prevent the base plate from tilting through the belt-pull acting on one side of the motor.

The loading device may consist of a rotatably mounted shaft carrying an actuating disk and connected with the base plate by means of a crank and link device, the links being attached at one end to the crank on the shaft, and at the other end to the base plate. When a lever which is arranged to rotate the disk and to which a weight is adjustably or otherwise attached makes the disk and the shaft revolve, the base plate, with the motor resting on it, is lowered by the crank and link device until the desired belt tension is obtained.

The disk carries on its outer surface a pin which is adjustable in position in any one of a number of holes arranged concentri-

cally with the shaft, and on this pin the lever rests. By changing the position of the pin on the disk it is possible to maintain the lever in an approximately horizontal position, even if the disk should be turned through a considerable angle or distance. 60

Instead of connecting the shaft to the base plate by the crank and link device for shifting the position of the plate, other appropriate means may be employed, for instance, a rack attached to the base plate 65 and cooperatively disposed between a suitably supported guide roller and a toothed pinion on the shaft may be employed.

A second pin is arranged preferably on the disk at a point which may be diametrically opposite the one on which the lever rests during the operation of the motor. By turning the lever over on to this second pin the belt can be released from tension so that no stretch of the belt can take place 75 whilst the plant is at rest.

An example of the invention is shown in the accompanying drawing, in which:—

Fig. 1 is a front elevation of the motor base plate and sub-base and parts carried 80 by them.

Fig. 2 is a side elevation; and

Fig. 3 a plan of the same.

Fig. 4 corresponds to Fig. 1, but shows the lever in a position when it becomes necessary to turn it back towards the horizontal by changing the pin in the disk to another hole.

The support for the motor *m* as shown, consists of upper channel- or other-shaped frame members *a*. Similar lower members *a'* and one or more cross members such as *d*. The members *a* and *a'* are connected by means of bolts *b*. The bolts pass through clearance holes in the upper frame members. Above and below these members the bolts carry lower and upper spiral springs *f*, *f'* which tend to lift the base plate or frame *a* and therefore the motor. Suitable means such as the nuts *f²* may be provided for adjusting the set of the springs. In order that the base *a* and therefore the motor, may not take up an inclined position under the effect of the one sided belt pull, the pairs of links *p* connecting the upper 100 and lower members *a*, *a'* together, are provided.

From a cross member *d* of the upper

frame links *e*, *e* are suspended. These links are connected at their power end, by means of a bolt, to a crank *g* fixed to one end of the shaft *k* which is supported in bearings *i*.
 5 On a squared portion at the other end of this shaft a disk *n* is non-rotatably attached.

Mounted to pivot on shaft *k* in front of the disk *n* is a lever *q* which carries a weight *q'* which may be made adjustable in position lengthwise of the lever. The lever may be retained on the shaft *k* by means of a nut *h* and is supported intermediate of its ends by a pin *r* screwed into or other-wise supported 10 on, the disk *n*. The position of the pin can be changed to any of the holes *o* provided on the disk.

After the motor is started, lever *q* is brought into the position shown on Fig. 1, 20 and tension is thereby put on the belt *s'*. In case the belt should stretch in course of time, the tension on the lower springs *f* is somewhat reduced so that the frame *a* is able to take a lower position, while lever *q* may assume a lower position as shown on Fig. 4.

In any case, in order to prevent the lower member from contacting with the floor on which the support rests and so be put out of action, the pin *r* on which the lever is seated 20 should be removed from the hole in which it is at the moment inserted, and be placed in one of the higher holes *o* on the disk *n* so as to support the lever in a nearly horizontal position.

In order to release the belt from tension, when the motor is not running, a second series of holes *o'* is arranged on the disk *n* diametrically opposite the series *o* for the reception of a pin *r'* on to which the lever can be turned in order to release the tension in the belt in consequence of the lifting of the upper frame *a* in conjunction with the motor.

I claim:—

1. An improved support for a motor to 45 maintain a proper tension in a motor driving belt, arranged vertically or nearly so, and for releasing the belt from tension when not in operation comprising in combination a base plate, vertical springs supporting said 50 base plate and a device for shifting the base plate against the action of the springs so as to keep the belt in uniform tension whilst the motor is running.

2. An improved support for a motor to 55 maintain a proper tension in a motor driving belt, arranged vertically or nearly so, and for releasing the belt from tension when not in operation comprising in combination an upper and a lower base member, screwed 60 bolts for connecting said members, springs on said bolts for carrying the upper base, and links connecting the upper and lower base members to prevent the motor from tilting under the effect of the one-sided belt 65 pull, and a lever and weight for operating the device for tensioning the belt.

3. An improved support for a motor to maintain a proper tension in a motor driving belt, arranged vertically or nearly so, 70 and for releasing the belt from tension when not in operation comprising in combination a base plate, a rotatably mounted shaft, a crank and link mechanism connecting the shaft and base plate, and a disk that is rigid 75 with the shaft, a lever and weight for revolving said disk and thereby causing the base plate to be lowered until the belt is sufficiently tensioned for the power transmission required.

In testimony whereof I affix my signature in presence of a witness.

PAUL SPILGER.

Witness:

BERNHARDT REISER.
